UNITED STATES PATENT OFFICE

2,448,741

ENDOSCOPIC SURGICAL INSTRUMENT

William W. Scott and August Lutz, Chicago, Ill.,
assignors to American Cystoscope Makers, Inc.,
a corporation of New York

Application April 25, 1945, Serial No. 590,208

8 Claims. (Cl. 128—303.15)

1

This invention relates to endoscopic surgical instruments used for examination and surgery within the cavities of the human body. While the preferred form of the instrument described and shown in this application is designed primarily for transurethral prostatic surgery, it is readily adaptable to other uses and is not limited to that specific purpose.

One of the objects of the invention is to provide an endoscopic surgical instrument which can be operated with greater facility and ease than similar instruments now in use and which can be more accurately located within a body cavity for use therein.

Another object of the invention is to provide an instrument of this type which can be operated through a wide range of movements with the least possible alteration in the position of the operator.

Another object of the invention is to provide an instrument of this type which permits quick assembly and disassembly, ready removal of the respective parts for interchange and cleaning, but nevertheless permits the related parts to be quickly and securely locked together without tools.

Still another object of the invention is to provide a surgical instrument of this type which may be manipulated with one hand leaving the other hand free for auxiliary manipulation. For example, when the instrument is used in prostatic surgery it can be operated with one hand leaving the other free for rectal palpation and third dimensional perception.

Another object of the invention is to provide an instrument of this type in which the handle or grip portion can be maintained in a stationary position while the working elements which are inserted in the body cavities can be rotated relatively to the grip portion and operated without any change in the manipulation in a full range of positions throughout the 360 degrees of rotation available.

A further object of the invention is to provide a surgical instrument of this type with novel means of securing the reciprocal cutting electrode in the instrument so that it cannot become detached during the use of the instrument.

Another object of the invention is to provide an instrument of this type in which the liquid and electrical leads leading to the instrument may remain in a fairly constant position with respect to the operating portions of the instrument thus reducing the interference of these leads with the manipulation of the instrument in the performance of surgery.

These and other features of the invention will be seen from the following detailed specification read in connection with the accompanying drawings forming part thereof and in which—

2

Fig. 1 is an elevation of the instrument of this invention in assembled condition ready for use;

Fig. 2 is a section through part of the grip member taken on the line 2—2 of Fig. 1;

Fig. 3 is a section through part of the grip member taken on the line 3—3 of Fig. 1;

Fig. 4 is a section through part of the grip member taken on the line 4—4 of Fig. 1;

Fig. 5 is a longitudinal middle section of the complete instrument shown in Fig. 1 omitting the water and electrical leads to the instrument;

Fig. 6 is a section through part of the grip member taken on the line 6—6 of Fig. 5;

Fig. 7 is a fragmentary section of the detent taken on the line 7—7 of Fig. 6;

Fig. 8 is a view in perspective of the reciprocal instrument carrier for the electrical cutting loop;

Fig. 9 is a fragmentary elevation in section of the proximal end of the carrier shown in Fig. 8;

Fig. 10 is a perspective of the distal end of the carrier showing the electrical cutting loop, light and telescope lens;

Fig. 11 is an elevation of the front end of the sheath and carrier showing various radial positions to which these parts may be turned without change in position of the grip member;

Fig. 12 is a perspective of a modified form of instrument carrier;

Fig. 13 is a perspective of a fragment of a second modified form of instrument carrier.

Referring to the drawings, the preferred form of the instrument herein will be described as a series of assemblies which are more or less related and which, when combined, form the completed instrument.

A. THE GRIP MEMBER

Referring to Fig. 1 showing the complete assembled instrument, the numeral 20 indicates the handle member which is generally hollow to contain the moving portions of the instrument and, if desired, may be covered with transparent plates 21 secured to the handle frame in the conventional manner. The handle 20 is preferably made of metal but may also be formed from other materials which can be suitably molded or cut into a shape which may be readily gripped by the human hand and which may be hollowed out to contain the moving parts of the instrument.

The handle member 20 is shown divided into a rear chamber 22 and a forward chamber 24. The rear chamber has a bottom wall 25 and a top wall 27 while the forward chamber 24 terminates in the forward wall 28. If desired, the two chambers 22 and 24 may be separated by an intermediate wall 26 which may also be employed to

serve as a support and bearing member for various parts of the instrument. The upper portion of the handle terminates in the back wall 30.

Entering into the chamber are the electrical leads 32 and 34. Lead 32 is shown as a monopolar lead for high frequency resecting and cauterizing current while lead 34 is a bipolar lead for low voltage illuminating current. These leads pass through the lower end of the grip member through the bore 36 (Fig. 5).

Secured to the back wall 30 of the rear chamber 22 are the lower insulating block 38 and the upper insulating block 42 upon which are mounted binding posts for the current leads 32 and 34. The high frequency lead binding post is numbered 40 and the illuminating current binding posts 44. These posts are electrically connected with the illuminating current brushes 46, while the binding post 40 for the high frequency current is connected to the high frequency current bus bar 48.

B. TRIGGER ASSEMBLY

Mounted within the grip member 20 is the spring chamber 52 within which is mounted the coil spring 54. Riding upon the spring chamber 52 is the trigger sleeve 58 to which is attached the trigger 56 which projects beyond the grip member and is reciprocable with respect thereto. The coil spring 54 bears against the trigger sleeve pin 60 which is connected to the trigger sleeve 58 and passes through a slot in one side of the spring chamber 52. The coil spring 54 thus forces the trigger back to its forward position whenever pressure upon the trigger is released.

Secured to the trigger is the fork 62 which projects into the forward chamber 24 to move the instrument carrier. This fork terminates at its upper end in a series of tines 64 which transmit the motion from the trigger to the instrument carrier.

C. WATER LEAD

Entering into the front wall 28 of the handle member is the water or liquid inlet tube 74 upon which is fitted the water lead 72. These are suitably bored for the discharge of water through a port in the front wall and therefrom into the forward end of the operating instrument.

If desired, the water lead may be located on the sheath 132 of the instrument to be later described herein, or upon the sheath mounting sleeve 106.

D. INSTRUMENT CARRIER ROTATOR ASSEMBLY

Referring to Fig. 5, there is mounted within the wall 28 the carrier bearing sleeve 76 which is drilled with a bore to connect with the water inlet tube 74 and forms a journal for the forward carrier bearing 78 which is also suitably bored and grooved to permit the flow of liquid from the inlet tube 74 forward into the operating instrument but is so closely fitted as to prevent the flow of liquid into the compartments of the handle member 20. At the rear end of the carrier bearing is the carrier rotating pinion or driving gear 80 and secured to the forward end of the carrier bearing is the carrier rotating wheel 82 which is suitably knurled or serrated to permit its ready manipulation by the finger. In order to prevent undesired rotation of the rotating wheel 82 the face of the wheel may be provided with detent seats 84. These may be radially arranged on the rotating wheel so as to pass before the

detent tube 86 (Fig. 6) within which is contained the detent spring 88 and the detent ball 90 designed to seat in the detent seats 84.

Directly forward of the rotating wheel 82 is the sheath nipple 92 which may be provided with a suitable latch 94 to secure the sheath to the grip portion of the instrument.

E. INSTRUMENT CARRIER AND RECIPROCATOR ASSEMBLY

10 Rotatably mounted within the forward chamber 24 is the instrument carrier or working member 102 which is snugly fitted in the forward carrier bearing 78 and may be further supported by 15 the rear bearing 104 mounted in the wall 26. Secured to the instrument carrier 102 is the instrument carrier driven pinion 106 which is embraced by the trigger fork tines 64 by which the instrument carrier is reciprocated upon movement of the trigger 56. Also suitably journaled within the forward chamber 24 is the intermediate gear 108 which is enmeshed both by the carrier rotating pinion 80 and the instrument carrier driven pinion 106. The intermediate gear 108 is elongated so that as the driven pinion 106 moves with the reciprocating instrument carrier 102, the engagement of the three gears, 80, 108, and 106 remains undisturbed.

At the rear end of the instrument carrier 102 30 is mounted the cutting current commutator 110 which bears the cutting current brush 112. This brush 112 remains in contact with the cutting current bus bar 48 as the instrument carrier 102 is reciprocated.

35 The commutator 110 is mounted upon the carrier insulating block 114 through which are cut the telescope bore and keyway 115 and the cutting loop shank bore 117. The latter is not cylindrical in form but has a flattened portion to fix 40 the radial position of the cutting loop shank when inserted therein. Also mounted on the carrier insulating block 114 is the cutting current contact 116 designed to form a contact for the cutting current electrode.

45 At the rear of the carrier insulating block 114 is pivotally mounted the cutting loop shank latch 118 which pivots upon the latch pivot 120. This latch, as best shown in Figs. 3, 8 and 9, has one straight edge which, when the pivot is swung 50 across the face of the carrier insulating block, partially crosses the cutting loop shank bore 117.

The reciprocable instrument carrier 102 terminates at its forward end in the tubes 122 and 124, the first of which is a telescope tube in which the 55 telescope and illuminating shaft is mounted and the second of which, 124, is a tube for the cutting loop shank (Figs. 5, 8 and 10).

The tube for the telescope shaft must permit 60 movement of the shaft within the tube as the tube is reciprocated with the instrument carrier in the preferred embodiment shown herein while the telescope and illuminating device remains in fixed position with respect to the grip portion of the instrument although it necessarily rotates with the instrument carrier.

In order to permit ready sterilization of the instrument carrier, its body 102 may be cut with a plurality of slots 100 to give quick access of 65 sterilizing liquid to the interior.

F. SHEATH

70 Detachably mounted upon the sheath nipple 92 is the sheath 132 which is designed for insertion in the body cavity in which examination or

operation is to be performed. The proximal end of this sheath bears the sheath shield 134 and the sheath mounting sleeve 136 which passes over the sheath nipple 92 and may be latched thereto by means of the latch key 138 which may be any conventional form. The distal end of the sheath is preferably cut away, as shown in Fig. 1, to expose the illuminating and cutting loop for access to the portion of the body under examination or operation.

If desired the sheath may be provided with a water intake similar to 74 entering upon the sheath mounting sleeve 136, or the intake may be mounted upon the sleeve 136.

The sheath is either made wholly of insulating material or is suitably insulated so that if it is engaged by the high frequency cutting loop it will not provide contact for electrical currents with the tissues with which the sheath is normally in contact.

G. HIGH FREQUENCY CUTTING ELECTRODE

The portion of the instrument by which surgery is performed is the high frequency electrode made up of the cutting loop shank 152, designed to be removably mounted within the cutting loop shank tube 124. This cutting loop shank 152 contains the insulator sleeve 156 through which passes the high frequency conductor 154. This conductor terminates in the cutting loop 158 which is insulated except for the bared loop portion designed to perform the resection or cautery. The cutting loop is supported by the cutting loop arms 160.

At the proximal end of the cutting loop shank 152 the high frequency conductor 154 is exposed so as to contact the cutting current contact 116. The shank 152 is also notched by the locking notch 162 designed to be engaged by the cutting loop shank latch 118 and to be disengaged when the latch is swung upon its pivot 120. The shank is also flattened on one side to insure its correct radial position with respect to the instrument carrier 102 and sheath 132.

H. TELESCOPE AND ILLUMINATOR

Removably mounted within the telescope tube 122 is the telescope shank 172 which passes through practically the full length of the instrument. This tube terminates in the light socket 176 in which is removably mounted a light bulb 178 and also carries the objective lens 174. The proximal end of the telescope shank terminates in the eye piece 180. Between the eye piece and the objective lens 174 and within the telescope shank is mounted a conventional lens system to permit the telescopic observation through the eye piece and objective lens of areas in proximity to the lens and within the illuminating range of the light bulb 178.

A portion of the telescope shank passing through the rear chamber 22 is provided with a telescope shank key 182 which is designed to fix the telescope with respect to the instrument carrier so that the objective lens 174 is always aligned with the cut away portion of the sheath 132. This shank key passes through the cutting loop shank latch 118 and the carrier insulating block 114 and thus immovably locates the cutting loop shank latch which is pivoted with respect to the carrier insulating block and the electrode shank when the instrument is assembled.

Shortly forward of the eye piece 180 is the commutator block 184 mounted upon the telescope shank. This commutator block bears an

outer commutator ring 186 and an inner commutator ring 188 which provide the contacts for the respective leads to the light bulb 178. When the instrument is assembled these rings bear against the brushes 46.

The commutator block is also cut with an annular groove 190 which is designed for engagement with the telescope shank keeper 192 which is secured to the handle member 20 by means of the keeper screw 194. The keeper 192 is slotted where the screw 194 passes through it so as to permit the keeper to be lifted free of the annular groove 190 so that the telescope shank may be removed from the instrument.

15

I. MODIFICATIONS

In Figs. 12 and 13 are shown two modified forms of the instrument carrier and reciprocator assembly which differ from the preferred form 20 described merely in the manner in which rotary motion is transmitted to the instrument carrier from the rotating wheel. In Fig. 12 the instrument carrier or working member 202 is shown without any driven pinion but with the carrier body slotted with the longitudinal keyways 208 which are snugly engaged with keys cut into the forward carrier bearing 278. The carrier is also provided with an annular flange 206 in the place of the driven pinion. This flange is embraced by the tines or fork on the trigger to reciprocate the carrier.

The forward carrier bearing 278 is mounted within the sleeve 276 in the same manner in which the other forms are constructed.

35 In the modification shown in Fig. 13 the instrument carrier or working member 302 is cut into a square shaft where it passes through the carrier bearing 378 which is mounted in the carrier bearing sleeve 376. This form is also 40 provided with the annular flange 306 to be engaged by the trigger fork for reciprocating the carrier.

In either of these modified forms the pinions and intermediate gear shown in the drawings 45 and described in the specification are eliminated.

Method of assembly

This instrument will normally be disassembled in part for sterilization and checking before each use. In disassembled condition the sheath 132 will be off the instrument, the telescope and illuminating assembly will be removed therefrom and the high frequency cutting loop will be removed from its mounting. With the instrument in this condition it is assembled for use by insertion of the cutting loop shank 152 into its tube 124 from the distal end of the instrument. The shank of the cutting loop is forced to its most rearward position through the carrier insulating block 114 and with the conductor 154 forced snugly into contact with the cutting current contact 116 to provide a certain electrical connection. Because of the flattened end of the cutting loop shank 152 the cutting loop will always be located in a fixed position with respect to the cutting loop carrier and thus alignment of the loop within the cut away portion of the sheath 132 determined.

70 The cutting loop shank latch 118 is then swung on its pivot 120 and an edge of the cutting loop shank engages the locking notch 162 in the shank and thus prevents the loop shank 152 from being withdrawn from the instrument carrier 102. This also insures that when the loop is

reciprocated in surgical use it will not be accidentally withdrawn from the instrument.

To lock the cutting loop shank latch 118 in position and thus positively prevent release of the cutting loop shank, the telescope shank 172 bearing the illuminating apparatus and lens system is inserted through the carrier insulating block 114, carrier 102, and telescope tube 122 from the proximal end of the instrument. The radial position of the telescope is determined by the key 182 on the telescope shank which is keyed both with respect to the latch 118 and insulating block 114. This insures that the telescope objective lens 174 will always be properly positioned with respect to the cutting loop 158 and the open portion of the sheath 132.

As the telescope is forced into its final position the commutator rings 186 and 188 are brought into contact with the brushes 46 to complete the circuit for the light bulb 178.

The telescope shank keeper 192 is then dropped into the annular groove 190 in the commutator block 184 and the keeper screw 194 tightened to lock the keeper in position.

The instrument is now ready for connection of the water lead 72 and the electrical leads which may either extend from the grip portion or may be made detachable by means of suitable electrical connections.

In conventional surgical practice the sheath is inserted into the body cavity before attachment to the instrument by means of an obturator which is withdrawn after the sheath has been properly located. The instrument may then be inserted into the sheath and because of the location of the sheath latch 94 on the sheath nipple 92, which is fixed with respect to the radial position of the telescope shank and the cutting loop shank, the open portion at the distal end of the sheath will be properly positioned with respect to these devices.

Method of operation

With the instrument inserted in the sheath within a body cavity the carrier rotating wheel 82 may be rotated through its full range of 360 degrees. As it is rotated the sheath, the telescope shank and the cutting loop shank are all simultaneously rotated with the instrument carrier to maintain fixed relation of these parts so that the objective lens always faces through the open portion of the sheath and the cutting loop has access through that open portion of the sheath to the tissues to be cut or cauterized.

If liquid is desired within the body cavity this may be run into the sheath through the lead 72 and will be held against discharge by means of the sheath shield 134 or the engagement of the body tissues about the sheath 132, depending upon the extent of insertion of the sheath.

The operator grasps the instrument by means of the grip portion 20 and places the forefinger, whether right or left hand, into the trigger 56. With the electrical connections established the flow of current is controlled by means of switches which are conventional accessories in this art and form no part of this invention. By means of a suitable switch the light bulb 178 is lighted and the interior of the cavity can be observed through the eye piece 180.

Thereupon the high frequency current may be run through the cutting loop and the loop reciprocated by means of the trigger 56 to cut an elongated portion from the tissue in contact with the cutting loop. As the tissue is cut away and

adjacent tissue must be brought within reach of the cutting loop, the carrier rotating wheel may be turned in either direction and all of the tissue adjacent to the distal end of the sheath thus brought within reach of the cutting loop without any alteration of the radial position of the grip portion.

In the preferred embodiment shown, movement of the trigger 56 reciprocates the instrument carrier 102 with the telescope tube 122 and the cutting loop shank tube 124, thus moving the cutting loop through its path but not imparting corresponding reciprocation to the telescope objective lens 174 and the light bulb 178, since the shank 172 upon which these are mounted slides freely within the telescope tube 122. If desired the instrument can be modified so that the objective lens and light bulb also reciprocate with the instrument carrier but this would require a reconstruction of the commutator and brushes for the illuminating circuit.

Naturally, in the manipulation of the instrument the grip portion will be swung upward, downward or laterally in order to press the cutting loop into contact with exposed tissue but the design of this instrument avoids the necessity for turning the grip portion from its fixed position, thus leaving the hand in a normal and fairly stationary position throughout the operation.

Because of the relative rotatability of the working position of the instrument and the grip portion, the water and electrical leads remain in fixed position and do not interfere with the operation of the instrument as they do when it is necessary to invert the handle or twist it into various radial positions.

Because of the design of the instrument with its pistol type of grip and its trigger mounting, the operation can be performed with a single hand, the forefinger being readily available to move either the trigger 56 or the rotating wheel 82.

The importance of the relative rotatability of the grip portion of the instrument and its working elements is particularly evident in prostatic surgery where it is frequently necessary to resect the prostate gland from the prostatic capsule. This instrument not only permits transurethral access to the prostate gland but readily permits the resection of the dorsal ventral and lateral portion of the gland by rotation of the sheath and the working elements of the instrument without any disturbance of the position of the grip or handle portion of the instrument. This eliminates a great deal of the change in position required of the surgeon where the entire instrument must be rotated into various radial positions and also maintains the water and electrical leads in a fairly constant position where they least interfere with the surgeon. Similarly, since the instrument can be wholly manipulated by one hand, the other hand is left free for third dimensional perception and rectal palpation.

The instrument with its working member 102 can readily be withdrawn from the sheath at any time by unlatching the sheath from the sheath nipple whereupon the entire instrument, with the exception of the sheath, can be removed from the situs of the operation.

At any time the telescope can be removed merely by loosening the keeper screw 194 and lifting the telescope shank keeper and withdrawing the telescope shank from the instrument. As the telescope shank is withdrawn, the con-

nections of the electrical illuminating system are automatically broken and a different type of telescope can readily be substituted for that last used in the instrument.

If a different type of cutting loop is desired the instrument may be withdrawn from the sheath during the operation, the cutting loop shank unlocked by removing the telescope shank, swinging the cutting loop shank latch 118 and withdrawing the cutting loop shank from its tube 124 and substituting another therefor.

The method of disassembly is substantially a reversal of the assembly of the instrument and need not be further described.

Having thus shown and described three embodiments of the invention, it is to be understood that it is capable of many modifications. Changes, therefore, in the construction and arrangement may be made without departing from the spirit and scope of the invention as disclosed in the appended claims, in which it is intended to claim all novelty inherent in the invention as broadly as permissible, in view of the prior art.

What we claim is:

1. A surgical instrument comprising a grip member, an instrument carrier mounted thereon, a cutting electrode mounted upon the instrument carrier, a latch mounted upon the instrument carrier to engage the cutting electrode and lock it to the instrument carrier, and a viewing tube removably mounted on the instrument carrier and engaging the latch to prevent its movement to unlocking position.

2. A surgical instrument comprising a grip member, an instrument carrier mounted thereon, a cutting electrode mounted upon the instrument carrier, a latch mounted upon the instrument carrier to engage the cutting electrode and lock it to the instrument carrier, a viewing tube removably mounted on the instrument carrier and engaging the latch to prevent its movement to unlocking position, an electrical contact upon the instrument carrier engageable by the electrode for passage of a high frequency current therethrough, and a pair of electrical contacts upon the grip member to engage complementary contacts upon the viewing tube when the viewing tube is mounted upon the instrument carrier.

3. A surgical instrument comprising a grip member, an instrument carrier mounted thereon, a cutting electrode mounted upon the instrument carrier, a latch mounted upon the instrument carrier to engage the cutting electrode and lock it to the instrument carrier, a viewing tube removably mounted on the instrument carrier and engaging the latch to prevent its movement to unlocking position, an electrical contact upon the instrument carrier engageable by the electrode for passage of a high frequency current therethrough, a pair of electrical contacts upon the grip member to engage complementary contacts upon the viewing tube when the viewing tube is mounted upon the instrument carrier, and means upon the grip member to engage the viewing tube to secure it against longitudinal motion with respect to the instrument carrier and grip member.

4. A surgical instrument comprising a grip member, an instrument carrier rotatably and reciprocally mounted therein, a rotating wheel mounted upon the grip member to rotate the instrument carrier, a sheath for insertion into a body cavity mounted upon the rotating wheel and rotatable therewith, a cutting electrode mounted upon the instrument carrier and movable therewith, a latch mounted upon the instru-

ment carrier to engage the electrode and secure it to the instrument carrier against longitudinal motion with respect thereto, an electrical contact upon the instrument carrier engageable by the electrode, an electrical contact within the grip member engageable by the contact upon the instrument carrier regardless of the position of the instrument carrier, a viewing and illuminating tube removably mounted upon the instrument carrier and rotatable therewith and engaging the latch to prevent its movement to unlocking position, a pair of commutator rings upon the viewing tube, a pair of complementary contacts upon the grip member, means upon the grip member to latch the viewing tube in position, and means upon the grip member to reciprocate the instrument carrier and the electrode therewith.

5. A surgical instrument comprising a grip member, an instrument carrier rotatably and reciprocably mounted upon the grip member, a cutting electrode removably secured to the instrument carrier and rotatable and reciprocable therewith, a telescope secured to and rotatable with the instrument carrier, means carried by the grip member for imparting reciprocation to the instrument carrier, and means carried by the grip member for imparting rotation to the instrument carrier with respect to the grip member through 360°.

6. A surgical instrument comprising a grip member, an instrument carrier rotatably and reciprocably mounted upon the grip member, a cutting electrode removably secured to the instrument carrier and rotatable and reciprocable therewith, a telescope secured to and rotatable with the instrument carrier, means carried by the grip member for imparting reciprocation to the instrument carrier, and means carried by the grip member including a wheel rotatable about an axis substantially coincident with the axis of the instrument carrier for imparting rotation to the instrument carrier with respect to the grip member through 360°.

45 7. A surgical instrument comprising a grip member, an instrument carrier rotatably and reciprocably mounted upon the grip member, a cutting electrode removably secured to the instrument carrier and rotatable and reciprocable therewith, a telescope secured to and rotatable with the instrument carrier, a sheath mounted on the grip member and rotatable with the instrument carrier, said sheath encircling the cutting electrode and the telescope, means carried by the grip member for imparting reciprocation to the instrument carrier, and means carried by the grip member for imparting rotation to the instrument carrier and the sheath with respect to the grip member through 360°.

60 8. A surgical instrument comprising a grip member, an instrument carrier rotatably and reciprocably mounted upon the grip member, a cutting electrode removably secured to the instrument carrier and rotatable and reciprocable therewith, a telescope secured to and rotatable with the instrument carrier, a sheath mounted on the grip member, said sheath being substantially coaxial and rotatable with the instrument carrier and encircling the cutting electrode and the telescope, means carried by the grip member for imparting reciprocation to the instrument carrier, and means carried by the grip member including a wheel rotatable about an axis substantially coincident with the axis of the instrument carrier for imparting rotation to the in-

11

strument carrier and the sheath with respect to the grip member through 360°.
